UNITED STATES PATENT OFFICE.

REGINALD A. FESSENDEN, OF BRANT ROCK, MASSACHUSETTS, ASSIGNOR, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

SIGNALING BY ELECTROMAGNETIC WAVES.

1,182,003.

Specification of Letters Patent.

Patented May 9, 1916.

Application filed April 19, 1906. Serial No. 312,724.

To all whom it may concern:

Be it known that I, REGINALD A. FESSENDEN, a citizen of the United States, residing at Brant Rock, in the State of Massachusetts, have invented a certain and useful Improvement in the Art of Signaling by Electromagnetic Waves, of which the following is a specification.

My invention relates to the sending of electrical signals and more particularly the generation of electro-magnetic waves for wireless telegraphy.

The primary object of the invention is the more efficient, certain and controllable production of oscillations, as hereinafter more fully described and claimed.

In the accompanying drawings forming a part of this specification Figures 1, 2 and 3 illustrate forms of apparatus for carrying out my invention.

The use of a spark for signaling by electromagnetic waves is very objectionable not only by reason of its inefficiency and considerable waste of energy, but also on account of the noise produced and its inconstancy in operation, the intensity of the signals varying from spark to spark. It is also objectionable in that as generally used it gives few impulses of short duration. By my method these objections are overcome, and the waves are produced efficiently without a spark gap.

In Fig. 1 is shown an induction coil having a core 1, a secondary coil 2, a primary coil 3, a break 4, and a condenser 5 shunted across the break. The induction coil is excited by any suitable means as for example by the storage batteries 6. The secondary coil 2 may have one terminal connected to the aerial and the other grounded as shown.

In the practice of my invention the inductance of the circuit containing the primary coils is made so as to be large compared with its ohmic resistance when the break 4 is closed. As the storage batteries 6 may have high resistance they may be shunted by the condenser 7.

The time which a current takes to rise in a circuit depends upon the time constant $\frac{L}{R}$ where L is the coefficient of self induction, and R the resistance.

The natural frequency of an electric os-

cillation depends upon the factor of $\sqrt{LC}$ where L is the coefficient of self induction 55 and C the capacity.

I so proportion the self induction of the primary 3, the ohmic resistance R of the circuit when the break 4 is closed, and the capacity of the condenser 5, that the current in 3 rises to the desired value during the time of closure of the break 4, and so that on the opening of the break, the natural period of the inductance 3 and capacity 5 is such as to generate oscillating currents of 65 the desired frequency in the antennæ, and thereby radiate electromagnetic waves. It is preferred to have the frequency of the circuit 3, 5, 6 equal to the natural frequency 70 of the antennæ circuit consisting of the antennæ, the secondary 2 and ground, and this is preferably done by adjusting the condensers 8, 5 and 7, all of which are preferably variable.

In order to make a sharp break it is preferred to inclose the break 4 in compressed air as shown, as I have found that by this means the break is made much more sharp and a much higher voltage can be produced.

In Fig. 2, is shown another form in which 80 9 is an inductance, 10 a rotating commutator revolving in compressed air, 11 a brush bearing on the commutator, 12 and 13 condensers, 14 a source of local voltage such as a storage battery or dynamo. 15 is an air-tight box inclosing the commutator 10 and brush 11 and filled with compressed air or a compressed inert gas or other insulator under compression.

The self induction of the coil 9 and the capacity of the condenser 12, the speed of the commutator 10 and the resistance of the circuit 9, 13, 10 is preferably made such that the current in the coil 9 rises to its desired value during the times the brush is passing 95 over one of the segments 14, of the commutator 10 as shown in Fig. 3, and when the brush is on the insulating segments 16 the oscillations take place through the circuit 9, 12, 13.

It will be seen that when the circuit controller comprising the commutator 10 and brush 11, or the break 4 is closed, the capacity 12 or the capacity 5 is short circuit-ed, and that when the circuit controllers 105 are open the capacity 12 is in series with the

inductance 9 and the capacity 5 is in series with the inductance 3.

5 Antennæ 16 16' alternately may be connect-
either directly as through the inductance 9
and grounded, or inductively through the
secondary 17 and grounded as shown. With
an ordinary induction coil it is found that
the frequency of the oscillations of the pri-
mary circuit will not, as a rule exceed 10,000
10 per second.

For the efficient generation of electro-
magnetic waves it is found in practice that
the height of the antennæ should not be less
15 than $\frac{1}{25}$ of the wave length and hence with
an ordinary type of induction coil the anten-
nae would have to be approximately 3,000
ft. high for the most efficient operation.
In the practice of my invention, however,
I so proportion the inductance of the pri-
mary and the capacity across the break that
20 frequencies as high as 100,000 may be ob-
tained in which case antennæ 300 ft. more or
less high give very efficient radiation. I
also prefer to adjust the capacities and in-
25 ductance in the primary or antennæ cir-
cuits so that the antennæ circuit is resonant
with the primary circuit, thereby obtaining
an increase in efficiency. I also prefer to
have as many breaks per second as possible.

80 I claim herein as my invention:

1. In apparatus for generating high fre-
quency oscillations, the combination of an
inductance, a circuit controller, a source of
35 current, and a capacity, said capacity being
connected so as to be short circuited when
the circuit controller is closed, and in series
with the inductance when the controller is

open, and a capacity in shunt to the cur-
rent source.

2. In apparatus for generating high fre- 40
quency oscillations, the combination of a
closed circuit having an inductance, a cir-
cuit controller, a current source and a ca-
pacity connected to the circuit controller
so as to be short circuited when the con- 45
troller is closed and connected in series with
the inductance when the controller is open,
and a capacity in shunt to the current
source.

3. Apparatus for generating high fre- 50
quency electrical oscillations directly from
a current source comprising a closed oscil-
lating circuit including an inductance, two
condensers, a current source shunting one
of said condensers and a circuit controller 55
intermittently shunting the other condenser,
substantially as described.

4. Apparatus for generating high fre- 60
quency electrical oscillations comprising an
antenna-to-ground circuit containing a ca-
pacity and inductance, a local closed circuit
including said inductance and capacity and
also a current source shunted by another
65 capacity, combined with a circuit controller
operating to alternately connect the capac-
ity in the antenna in series and in shunt in
the antenna at high frequency.

In testimony whereof, I have hereunto
set my hand.

REGINALD A. FESSENDEN.
